UNITED STATES PATENT OFFICE.

FRANK S. RITTER, OF PHILADELPHIA, PENNSYLVANIA, ASSIGNOR TO UNITED STATES
POSTAL CARD ADVERTISING COMPANY, A CORPORATION OF DELAWARE.

DESIGN FOR A POST-CARD.

40,754.

Specification for Design.

Patented July 5, 1910.

Application filed April 1, 1910. Serial No. 552,935. Term of patent 7 years.

To all whom it may concern:

Be it known that I, FRANK S. RITTER, a citizen of the United States, residing in the city and county of Philadelphia, State of Pennsylvania, have invented a new, original, and ornamental Design for Post-Cards, of which the following is a specification, reference being had to the accompanying drawing, forming a part thereof.

The figure is a plan view of the reverse of a post card showing my new design.

I claim:—

The ornamental design for a post card, as shown.

FRANK S. RITTER.
